UNITED STATES PATENT OFFICE.

ARTHUR WEIGELT AND WILLIAM HERMS, OF ST. LOUIS, MISSOURI.

DESIGN FOR A SCAFFOLD FOR MECHANICAL JUMPING FROGS.

SPECIFICATION forming part of Design No. 30,033, dated January 17, 1899.

Application filed December 19, 1898. Serial No. 699,779. Term of patent 3½ years.

To all whom it may concern:

Be it known that we, ARTHUR WEIGELT and WILLIAM HERMS, citizens of the United States, residing in the city of St. Louis, State of Missouri, have invented and produced a new and original Design for a Scaffold for Mechanical Jumping Frogs, of which the following is a specification.

Figure 1 is a front elevation of a scaffold 10 for the mechanical jumping-frog embodying our new design, and Fig. 2 is a bottom plan as seen looking in the direction indicated by the arrow.

As shown in the drawings, the leading or essential feature of our new design consists of

the plate 3, having the openings 4 one above the other, the straight-wired side edges 5 and 6, the rounded wired upper edge 7, and the wire posts 8 and 9, extending downwardly from the wired edges 5 and 6. 20

We claim—

The design for a scaffold for the mechanical jumping frog, substantially as herein shown and described.

ARTHUR WEIGELT.
WILLIAM HERMS.
